UNITED STATES PATENT OFFICE.

WILLIAM D. FOREMAN, OF CHICAGO, ILLINOIS.

TIMING DEVICE FOR JUMP-SPARK IGNITION SYSTEMS.

No. 889,450.

Specification of Letters Patent.

Patented June 2, 1908.

Application filed July 5, 1907. Serial No. 382,226.

To all whom it may concern:

Be it known that I, WILLIAM D. FOREMAN, a citizen of the United States, residing at Chicago, in the county of Cook and State of Illinois, have invented a new and useful Improvement in Timing Devices for Jump-Spark Ignition Systems, of which the following is a specification.

My invention relates to improvements in devices for timing the spark and thereby regulating the explosion in gas and gasoline engines, and is more especially designed for use in engines with which automobiles are equipped. A device of this character as generally constructed comprises an adjustable stationary member provided with a circular series of contacts and a rotary member (usually the valve-shaft or cam-shaft of the engine) journaled in the adjustable stationary member and carrying a brush adapted to be rotated against the contacts, the rotating member being connected with the battery in a sparking circuit, and the wire leading therefrom being grounded on the engine. In operation, as the brush successively breaks connection with the contacts, electric arcs are produced with the result of forming deposits upon the contacts, which, in the continued operation of the device, accumulates to such an extent as to render the contact imperfect, thus impairing the efficiency of the device. Furthermore, it has been the practice to ground the current from the brush through the shaft or rotary member and the bearings in which the shaft is journaled, with the result that, by reason of wear in the bearings and the presence of lubricant therein, imperfect conductivity ensues, causing failure or irregularity of explosion in the engine.

My object is to overcome these defects, and this I accomplish by providing a novel construction of device which, in its operation, will cause the contacts to be automatically cleaned, and by which the current is reliably grounded.

Referring to the accompanying drawings— Figure 1 is a view in front elevation of my improved timing-device, with the cap or face-plate removed; Fig. 2, a section taken at the line 2 on Fig. 1, and viewed in the direction of the arrow; and Fig. 3 is a section through the binding-post and contact-member, taken at the line 3 on Fig. 2, and viewed in the direction of the arrow.

In the drawings 4 indicates the valve-shaft

or cam-shaft of an engine, with one of its bearings shown at 4¹, and upon the end of the shaft is a head or rotary member 5 confined to rotate therewith by means of a set-screw 60 passing through a flange 7 at one end of the head, which terminates at its opposite end in a reduced portion 8, forming a shoulder 9 against which is confined a washer 10. Journaled upon the head and confined between the flange 7 and washer 10, is a sleeve 11 carrying a disk 12, and projecting from the latter is an arm 13 to which is pivoted a rod 14 for the purpose hereinafter explained.

Upon the face of the disk is fastened, as by 70 bolts, a ring 15 formed of any desired insulating material arranged to concentrically surround the reduced portion 8 of the head or rotary member, and secured in the ring, to conform to and be flush with its inner surface, is a series of countersunk metal contact-pieces 16, of a number corresponding to the number of cylinders of the engine with which it is desired to use the device. These pieces, of which four are shown in the present case, 80 are spaced uniformly apart, and each is held in place by a shank 17 passing through the ring 15 where it is threaded to receive a binding-post 18.

Extending through the reduced portion 8, 85 transversely thereof, and retaining the washer 10 in place, is a tube 19, of somewhat less length than the internal diameter of the ring, being fastened centrally within said reduced portion in any desired manner to prevent its movement therein. Fitting loosely within this tube, at one end, is a contact-brush 20, while similarly fitting its opposite end is a socket-member 21 formed of insulating material, adapted to receive a wiper 90 22 for cleaning the contact-pieces 16. This wiper may be formed, as represented, of a strip of wire gauze, preferably brass, wound upon itself to a size just sufficient to permit of its being crowded into the socket-member 21, and interposed between this member and the brush 20 is a spring 23 for the purpose of forcing the socket-member and brush apart and thereby insuring their engagement with the inner surface of the ring 15 and the faces 105 of the contact-pieces 16.

Secured on the ring is a covering-cap 24 for inclosing the brush, contacts and wiper against the access of dust and moisture. I provide upon the cap an annular flange 25 to 110 overlap and tightly fit the ring 15. A binding-post 26, chambered from its inner end, is

- screwed into a boss centrally located on the cap, its inner end being preferably spun down around a spring-pressed contact-plunger 27 to inclose a flange 28 upon the latter.
- 5 A stem extends back from the contact-plunger and enters a hole in the binding-post beyond its chamber to furnish a guide for the contact-plunger which is normally forced outwardly by a spring 29 within the chamber 10 surrounding the stem and bearing against the flange 28.

In practice, as hereinbefore stated, this timing-device ~~is~~ is usually placed upon the valve-shaft or cam-shaft of the engine, as indicated in the drawings, but it may be otherwise placed and suitably geared to such cam-shaft to rotate in unison therewith; and the device is wired with the engine and other parts in the customary manner to produce, 20 in operation, the desired electric circuits, but this being well known in the art and forming no part of my invention it is not necessary to illustrate it in the drawings.

In constructing a timing-device of this character, provision must be made for adjusting the series of contacts around the brush and in relation thereto while the engine is running, and this is made necessary by the fact that under certain conditions it is 25 essential (to produce the best results) to cause the explosions in the various cylinders of the engine to take place earlier or later with the pistons of the respective cylinders at given points in their reciprocations. Provision is made for accomplishing this adjustment by mounting the disk, to which is attached the ring carrying the electric contact-pieces upon the movable member, as heretofore described and shown in the drawing, and 30 by attaching to the arm 13 on the disk 12 the rod 14 leading to any suitable point of operation.

What I claim as new, and desire to secure by Letters Patent, is—

45 1. In a timing-device of the character described, the combination with a rotary member and an adjustable stationary member provided with electrical contact-pieces, of a brush carried by said rotary member, and 50 a contact-cleaner slidably supported on said rotary member to be movable relative thereto.

2. In a timing-device of the character described, the combination with a rotary mem-

ber and an adjustable stationary member 55 provided with electrical contact-pieces, of a brush and a spring-pressed contact-cleaner supported on said rotary member.

3. In a timing-device of the character described, the combination with a rotary member 60 and an adjustable stationary member provided with electric contact-pieces, of a brush and a contact-cleaner composed of metal gauze carried by and insulated from the rotary member to coöperate with said 65 contact-pieces, for the purpose set forth.

4. In a timing-device of the character described, the combination with a rotary member and an adjustable member provided with electrical contact-pieces, of a brush carried 70 by said rotary member, a socket-member of insulating material confined in the rotary member, and a metallic contact-cleaner in said socket, for the purpose set forth.

5. In a timing-device of the character de- 75 scribed, the combination with a rotary member and an adjustable stationary member provided with electrical contact-pieces, of a brush and a contact-cleaner carried by the rotary member and spring-pressed to extend 80 them against said contact-pieces, for the purpose set forth.

6. In a timing-device of the character described, the combination with a rotary member and an adjustable stationary member 85 having a ring provided on its inner surface with a series of contact-pieces, of a brush and a contact-cleaner carried by the rotary member, and comprising a tube, the sliding brush and the cleaner being in opposite ends of the 90 tube, and a spring interposed between said brush and wiper, for the purpose set forth.

7. In a timing-device of the character described, the combination with a rotary member and an adjustable stationary member 95 having a ring provided on its inner surface with a series of contact-pieces, of a tube carried by the rotary member, a brush slidably confined in one end of the tube, a socket-member of insulating material in the opposite end of the tube, a contact-cleaner in said 100 socket-member, and a spring interposed between said brush and socket-member, for the purpose set forth.

WILLIAM D. FOREMAN.
